UNITED STATES PATENT OFFICE

ALBERT L. MOREAU, OF WILKINSBURG, PENNSYLVANIA, ASSIGNOR TO WESTINGHOUSE ELECTRIC & MANUFACTURING COMPANY, A CORPORATION OF PENNSYLVANIA

SUPERVISORY CONTROL SYSTEM

Application filed August 9, 1927. Serial No. 211,682.

My invention relates to signalling systems and, more particularly, to the selective control and supervision of remotely disposed apparatus units in a power system.

5 An object of my invention is to provide means for synchronously operating chains of relays to select apparatus units for operation and supervision.

Another object of my invention is to provide means for identifying the selecting position of the synchronously operated chains of relays at each position.

Another object of my invention is to provide means for operating a plurality of 15 groups of synchronous selecting relays at each station in synchronism.

Another object of my invention is to provide means for preventing operation of a synchronous relay system comprising a plurality of groups of relays at each station, when relays in non-associated groups energize simultaneously.

Another object of my invention is to provide means for operating chains of relays in 25 synchronism by means of code combinations of impulses.

Another object of my invention is to provide means for restoring the chains of relays to their normal position should they fall 30 out of step.

Another object of my invention is to provide means in a synchronous system for transmitting code combinations of impulses to operate selected apparatus units.

35 Another object of my invention is to provide means for remotely connecting two synchronous power systems to each other while in proper phase and synchronism, employing therefor operation control in a synchronous 40 relay system.

Another object of my invention is to provide means for controlling the operation of a driving circuit which operates two chains of relays in synchronism by the correct receipt of 45 supervisory signals.

Another object of my invention is to provide means for controlling the impulses over a drive circuit by supervisory signals.

50 Another object of my invention is to provide means for operating relays at two re-

motely disposed stations in synchronism by means including two independent circuits each operating from an individual station controlling each other.

Another object of my invention is to provide 55 means for operating a selected apparatus unit with a single impulse in a synchronous relay system employing code combination of impulses on all other points for operating selected apparatus units.

60 There are other objects of my invention, which together with the foregoing will appear in the specification which follows:

A major factor in the development of a 65 signalling system for selectively controlling and supervising large units of electrical power systems resides in the accuracy of the selective operation which can be obtained. While in all other signalling system such as telegraphy and telephony, a reasonable percentage of error in the selection is permissible, supervisory control systems on the other hand, must operate with infallible accuracy. 70 Failing to make an accurate and correct selection, it is essential that the system make no 75 selection and that the dispatcher be apprised immediately of the failure in the system so that correction can be made and the system be in operative condition again as soon as possible.

80 Another characteristic of supervisory control systems which distinguishes them radically from other signalling systems, resides in the fact that it is called upon to give comparatively little service as compared with 85 most signalling systems, but at the same time, each service that it does perform must be accurate and the system must be in preparation at all times for supplying that service. Since the system must be idle most of the 90 time, therefore, it is desirable to maintain it normally in a non-operating condition and to start it into operation automatically as soon as it is called upon to perform any kind of service, either to control or to supervise or 95 both.

Supervisory control systems have already 100 been developed in which chains of selecting apparatus remotely disposed from each other have been operated in synchronism by means

of chains of relays which counted the impulses, these latter relays energizing, locking up, and remaining locked until the completing of the cycle of operation. It is desirable, however, to maintain a minimum load on the batteries at the stations and this can best be accomplished by maintaining as few relays energized at one time as possible. In the present arrangement, provision is made for sequentially deenergizing as well as energizing the counting relays so that a minimum of these are maintained energized at any one time and the load on the battery considerably reduced.

It is also highly desirable to operate selecting apparatus at as high a speed as possible in order that signalling impulses indicative of a change of an apparatus unit are received at the office as soon after an operation as is possible. At the same time the speed of selector operation must not be such as to prevent or cause a loss of a supervisory signal due to the signal not being received before the selecting apparatus steps on to the succeeding point. This is overcome in the present invention by arranging to have the supervisory signal momentarily take control of the selecting apparatus operation, preventing the operation of the selecting apparatus until the supervisory signal has been corrected. While synchronous operation of selecting apparatus has been found to be the most practical method of selection for remotely controlling and supervising circuit breakers or other electrical units, there is a possibility, in cases where the systems are subjected to severe inductive surges, such as that induced by adjoining power systems, of false operations since the units in such a system are directly connected to the signalling line. Surges impressed on a signalling line may therefore cause a false operation of the unit which at the time of the surge is associated with the signalling line. In order to overcome this difficulty arrangements are provided whereby, after the unit has been selected by a synchronous selecting system, a code combination of impulses is transmitted over the signalling line for finally operating the selected unit. In this manner, surges do not have any effect on the apparatus unit since a predetermined code is required to operate the unit. When, however, it is desired to connect two remote alternating current systems, the relative phase and synchronism of these systems is indicated on a local synchronoscope by impulses controlled by the power systems and transmitted over the signalling lines. It is obvious that as soon as the proper phase and synchronism is obtained, the systems should be instantly connected.

It would not be practical, therefore, to transmit a code combination of impulses for connecting the system. By the time such a code has been correctly received the system

may again be out of synchronism. Where remote systems are to be connected when in phase and in synchronism, it is desirable to connect them by a single impulse. At the same time, provision must be made against the operation of the unit connecting these systems, by a surge coming, as this unit is associated with the signalling line. This is provided for in the present case by a simple and expeditious arrangement for connecting the two remote systems depending on their relative phase and synchronism by the mere selection of the succeeding point. At the same time should the unit be stepped over during the selection of other points a single surge impulse will not operate this unit. By this arrangement a single impulse operates a selected unit which at the same time is protected from surge effect of any power system. In order to prevent false selecting operation, each selecting point is identified by a check circuit which must be completed and causes the operation of predetermined relays before the final selecting point is completed and control and supervision operations can be performed. Should the check circuit fail to operate, provision is made for automatically conditioning the apparatus at the remote station to be reset while at the same time holding the final operating circuit open. At the same time a warning signal is transmitted to the dispatcher at the office end that the apparatus is out of synchronism and ready to be reset. The dispatcher can then tell from the point at which the apparatus has come to a stop, approximately where the trouble has occurred and can reset the apparatus to its normal non-operating condition by operating a reset key. False selections are thus prevented.

In order to prevent bulkiness of the system, where a large number of units are to be operated, the selecting apparatus is divided into groups usually ten in each group. The first ten selecting points are selected in sequence and then the common operation apparatus shown in the Figures 3 and 4 are switched over to select the next ten, and so on. In the switching operation, it may happen that the battery at one of the stations momentarily fails, in which case the selection will be repeated for the first ten while at the remote station where the battery did not fail, selection would be made for the second ten. Since the selecting operations are arranged to be repeated for each group, no provision is usually made for detecting the false or non-synchronous condition due to operations in incorrect groups. By providing a dummy point in the first group, in the present case, this difficulty is overcome, since the dummy point is not like any other selecting point and does not reappear in the other groups. If a station battery fails at any point in the selection so that the first group is reoperated

while another group is operated at the remote station, the dummy point will be first selected and since it will not check with any of the other points in the other groups, selection will be stopped in a manner equivalent to that described above in connection with a non-synchronous condition.

Referring now to the drawings,

Figures 1 to 3 are diagrams of the circuits and apparatus at the dispatcher's office, and

Figures 4 to 6 are diagrams of the circuits and apparatus at the substation.

Fig. 7 is a diagram of the circuit showing the relation between two succeeding groups of selecting relays.

Referring more particularly to Fig. 1, the lamp 101 is a flicker lamp which periodically goes on and off to advise the dispatcher when the selecting apparatus is started into operation from its normal non-operating condition so that he will watch for supervisory signals. The key 102 is the alarm key which the dispatcher may operate to stop the flickering operation of the flicker lamp 101 after the selecting apparatus has returned to its normal non-operating condition. Lamp 103 is a stop lamp individual to a selecting point and is characteristic of equivalent lamps at each selecting point. This lamp is illuminated as the selecting apparatus reaches the position individual thereto and the dispatcher is thereby informed of the position of the selecting apparatus. The key 104, 105 is the stop key of the type which remains in the position set and is also individual to each selecting point. By operating the stop key, to the open position shown, the selecting apparatus can be brought to a stop at the position individual thereto or, if the stop key is left in its unoperated position, the selecting apparatus will continue and step over this selecting point to the succeeding point. This key is shown in the operated or open position. Key 112, 113 is an operate twist key individual to a selecting position, there being an equivalent one for each of the other selecting positions. By operating these keys, the desired kind of control operation on the individual unit associated with that particular selecting point at the remote station can be performed.

Thus, with this key in one position, a circuit is prepared for transmitting impulses for operating the circuit breaker to its closed position, or with the key in its alternate position, a circuit is prepared for transmitting impulses for operating the circuit breaker to its open position.

The lamps 114 to 117 are individual to each selecting point. The lamp 114 when illuminated indicates that the twist key 112, 113 is in disagreement with the condition of the apparatus unit. That is, if the twist key has been moved to its closed position, to close the circuit breaker and thereafter for some reason the circuit breaker has auto-

matically tripped, the twist key would ordinarily be in position indicating that the circuit breaker is closed whereas actually it is tripped. Under such circumstances, the lamp 114 is illuminated to indicate that the twist key and the circuit breaker are in disagreement. The lamp 116 is illuminated to indicate that the circuit breaker is in its tripped position, lamp 115 is illuminated to indicate that the circuit breaker is in its closed position, and lamp 117 is illuminated to indicate the position of the selecting apparatus. This lamp illuminates when the selecting apparatus has reached the selecting point individual to this lamp. The keys 118 to 121 are the trip and stop keys individual to the second point. Similarly, the lamps 124 to 127 and keys 128 to 133 are individual to the succeeding selecting point.

The key 134 is a reset key, which as will be described hereinafter, functions to cause the selecting apparatus to be reset to its normal non-operating position at any point in the operation. The lamp 135 flickers to indicate that the selecting apparatus is in synchronous operation. Lamp 136 illuminates when the selecting apparatus starts into operation and indicates that the set is running. If lamp 136 is illuminated and 135 does not flicker, the dispatcher is warned that there is trouble.

The key 137 is a start key. In order to start the chain into operation, the key 137 must first be closed as will be described hereinafter. Lamp 138 is a normal white lamp indicating that the apparatus is in normal non-operating condition.

The key 139 is the master control key. When the proper unit has been reached and the operate key has been moved to the proper operate position, the master key is closed to impress the necessary energy upon the line for performing the desired operation on the unit. The relay 141 is a supervisory receiving relay individual to each selecting position and operates in accordance with the condition of its individual apparatus units for operating the signalling lamps.

The synchroscope 145 is operated at its individual position in the selecting system by impulses received from the remote substation to indicate when two individual power circuits are in phase and in synchronism for remote synchronizing. The relay 153 functions to permit the apparatus to be restored to its normal conditions even though the final operating control impulse is about to be transmitted for performing a desired operation. This relay also functions to complete an energizing circuit for relay 149 which connects the synchroscope into the system at the completion of the operation control code, when a single impulse will operate the remote unit.

Referring to Fig. 2, the relays 210 to 219 are indicative of the selecting relays indi-

vidual to each point. Although only ten such selecting relays are shown in the illustration, it will be understood that any number of selecting relays may be employed in my system. Individual to each of these selecting relays is a switchover relay 200 to 209. These relays are arranged to energize following the operation of their individual selecting relay for transferring the operating impulse from the drive relay to the succeeding selecting relay. It will be noted that each selecting relay is locked over the back contact of individual switchover relay so that when its switchover relay energizes, the selecting relay is deenergized. Similarly, each switchover relay is in turn held energized over the back contact of the succeeding switchover relay so that upon the energization of the succeeding switchover relay the preceding switchover relay is deenergized. In this manner the relays are all normally maintained deenergized and only two relays, a selecting and a switchover relay are energized at any one time.

25 Referring to Fig. 3, relay 300 is a supervisory receiving relay energized in response to the receipt of a supervisory signal indicating a closed condition of the apparatus unit and repeats the impulse to the proper individual supervisory signalling relay such as relay 141. Similarly, the relay 301 is the common trip relay energized in response to the receipt of a supervisory trip signal indicating that the circuit breaker individual to the particular point is tripped and transfers the impulse to the individual supervisory receiving relay such as relay 141. Relay 312 cooperates with the relays 300 and 301 to control the drive circuit and prevent further operation thereof until the supervisory impulse has been fully received and the local operation properly performed in accordance with the operation of the remote apparatus unit. This will be more apparent from the detailed description which is to follow.

The relay 313, when energized, in turn, controls the drive circuit under control of the relays 300, 312 and 318 and of the stop key. The relay 318 in turn is directly controlled from the stop key. With the stop key individual to each point in its operate position, the relay 318 will not be energized. If the stop key is left in its non-operate position, a circuit will be completed for the relay 318 which, in turn, completes an energizing circuit for the relay 313 which, upon energizing, opens the circuit for the driving relay 314 at armature 346. These operations are described in detail in the description of operations which follow hereinafter.

The relay 314 is the driving relay which periodically energizes as the relay 313 energizes and deenergizes to transfer impulses to the selecting relays. Upon each successive energization of the relay 314, an impulse is

transferred to the selecting relay through contacts of the switchover relays which, as pointed out above, determine which of the selecting relays is to be energized. Thus, the first time the relay 314 energizes, it completes an energizing circuit for the first selecting relay and the second time relay 314 energizes, a circuit is completed through the switchover relay to energize the second selecting relay and so on. The polarity of current for the drive relay 314 is determined by the energization or deenergization of the relay 315 which, in turn, is controlled from the switchover relays in a manner to be described in detail hereinafter. During the first four operations the relay 315 is maintained deenergized and energy is transmitted from the negative side of battery at the office to the relay 314, but after the energization of the fourth selecting relay, the relay 315 is energized and the polarity of current through the relay 314 is reversed in a manner which is described in detail hereinafter.

The relay 333 is a normal holding relay energized over the back contact of armature 362' in series with a normal holding relay at the remote station. The relay 322 which controls the energizing circuit for the relay 333 is energized by closing the start key and opens the energizing circuit for the normal holding relay 333. Energization of relay 322 starts the selecting apparatus into operation.

The relay 319 is energized following the operation of each selecting relay at the office and substation for indicating that the selecting relays are in synchronism. If the relay 319 does not energize following the energization of a selecting relay, this indicates a non-synchronous condition and will cause operations of relays for restoring the apparatus to normal in a manner to be described in detail hereinafter. Relay 320 energizes following the energization of the synchronizing check relay 319 to in turn energize relay 321. The energization of the relay 321 transfers the control and supervisory line to their final operating position and at the same time opens the circuit of the synchronizing relay 319.

The relay 331 energizes if two selecting relays energize simultaneously at the office or if any other than the correct selecting relay has energized, and functions to complete an energizing circuit for the relay 334 which controls the energizing circuit for the relay 322 and causes this relay to deenergize, thereby preparing the original holding circuit for the relay 333 which upon energization would restore the apparatus to normal by removing ground from all of the locking circuits at armature 337 in a manner to be described in detail hereinafter. The relay 331 also energizes at the end of the energization of the last selecting relay in the system to restore the apparatus to normal. Relays 330 and 331 cooperate with the relays 332, 329 and 334 for per-

forming the restoring operation during either a non-synchronous condition or the final operation of the last selecting relay. Relays 324, 325 and 326 are energized when the selecting apparatus starts into operation for operating flicker lamp 101.

In order that a large number of units may be operated it is advisable to divide the system into groups of small numbers as for example ten in each group. Arrangements are provided for switching over to the succeeding group of ten at the end of each group. During the switching operation, it may happen that the battery at one end is momentarily removed due to some accidental cause and instead of switching on to the succeeding group, the first group of selecting apparatus starts all over again, while the second group is operating at the remote end. In order to prevent this a dummy selecting point is provided at the beginning of the first group which is different from the first point of the succeeding group, so that the check circuit does not agree. This is accomplished by means of relays 316, 317 and 327 which comprise the normal first selected point although not an actual selecting point and does not complete a check circuit. Since the check circuit is not completed the selecting action is stopped and the control and supervisory lines 335 and 362 are opened, thus preventing any false operation of the apparatus units.

Following a selection of an apparatus unit, instead of transmitting a single impulse to operate the unit, a code combination of impulses are transmitted. This code is called an "operation control" code. The relay 303 energizes in response to the operation of a closing key for determining the code which is to be transmitted for a closing operation and the relay 305 energizes to determine the code which is to be transmitted for performing a trip operation. The relay 306 is part of this code transmitter and is periodically energized under control of an impulse transmitted from the remote station and under control of the relay 308, the circuit being opened from the remote end as will be described in detail hereinafter. Relays 307 to 315 are energized in sequence in response to the transmission of these code impulses in a manner to be described in detail hereinafter and the relay 302 is maintained energized during the transmission of these codes until the end of the operation, relay 302 indicating when the complete code has been transmitted.

Referring now more particularly to Fig. 4, relay 421 is the normal holding relay energized over the line in series with the relay 333. The relay 421 when deenergized starts the apparatus into operation and when energized opens the locking circuits of certain relays to restore the apparatus to normal.

Relay 414 is the driving relay which is periodically energized to transfer energiz-

ing impulses to selecting relays. The polarity of the current on the relay 414 is determined by the relay 415 which is maintained deenergized during the operation of the first four selecting relays and energized during the operation of the second group of four selecting relays. Upon each energization of a selecting relay, the relay 412, which is a check relay, is energized and determines thereby whether the correct selecting relay has energized. Upon the energization of the check relay 412, the relay 411 energizes which in turn completes an energizing circuit for the relay 410. The relay 410 switches the control and supervisory line through their final operating position, these circuits being normally maintained in non-operating conditions during the normal operation. Upon the operation of the relay 410, indicating that the proper switching operation has been performed, relay 413 energizes to open the energizing circuit for the check relay 412. In order to prevent an inaccurate operation, following the switching from one to another chain of relays, the relays 416, 417 and 425 function as an extra or dummy selecting point in a manner which has already been described briefly above and will be described in more detail hereinafter. Relay 419 is periodically energized from the contacts of the driving relay and being a slow release relay, remains energized during the operating period between the energization of the drive relay. Upon deenergization of the drive relay for longer than the normal period, this relay deenergizes and starts the restoring apparatus into operation for restoring the apparatus to normal. Relays 418 and 420 cooperate with relay 419 for restoring the apparatus to normal.

Relays 422 to 424 operate in response to the operation of two selecting relays or any selecting relay other than the correct selecting relay for restoring the apparatus to normal. If an automatic operation of a unit takes place during the period while the apparatus is in operation, relays 426 and 427 operate to store the supervisory impulse for later transmission after the selecting apparatus has gone through its cycle of operations and restarted. Relay 408 functions to switch the supervisory and drive line at the end of a certain number of selecting operations so as to reverse the functions of these two lines.

Relay 400 receives the periodic impulsive for transmitting the code operations for "operation control", the circuit for this relay being controlled from the remote end. Relays 401 to 405 inclusive are sequentially energized by the code impulses, and relays 406 and 407 determine the operation to be performed, that is, a trip or a closed operation.

Referring now to Fig. 5, relays 510 to 519 are the individual selecting relays and the relays 500 to 509, the switchover relays, each

switchover relay being individual to a selecting relay and functioning upon energization to transfer the energizing circuit from the drive line relay to the proper selecting relay.

5 Referring to Fig. 6, two circuit breakers are shown, 617 and 620. It is understood, of course, that these are merely illustrative for any number of circuit breakers, one for each of the selecting points. Relays 600, 601, and 10 611 to 614 are individual to the circuit breaker 617, and the operating magnets 615 and 616 perform the operations on the circuit breaker. The circuit breakers, it will be understood, may be automatically operated; the apparatus 15 associated with the other circuit breaker 620 is illustrative of an arrangement whereby remote synchronization can be obtained with this system in which synchroscope readings are transmitted over the normal control 20 and supervisory line. A code of impulses for performing the control operation is previously transmitted in the case of remote synchronization for setting up the proper condition so that when the synchronous condition 25 is reached, only a single impulse is necessary to perform the desired operation. This is accomplished by the relays 602, 603, and 604 to 606 in a manner which will be described in detail hereinafter. The relays 607 and 30 608 are the intermediate relays for closing the circuits to the trip or closed solenoids 609 and 610 which in turn close circuits to the operating magnets 618 and 619 of the circuit breaker 620.

35 Having now described the apparatus employed in my system, I will now describe the operation which takes place in selectively operating an apparatus unit in order to provide a better understanding of the invention.

40 Although I have shown a plurality of batteries both at the office end of my system (Figs. 1-3) and at the substation end (Figs. 4-6), it is obvious that only one battery, such as 335, at the office and a similar battery 429 45 at the substation will be necessary. The conductor C_m , connecting the batteries 335 and 429, is the common return conductor of the system.

With the system at rest, there is a normal 50 holding circuit completed from the positive side of battery 335, Fig. 3, conductor 336, through the winding of the relay 333, the back contact and armature 362', the control line 335, the armature 428 and its back contact, and through the winding of the relay 421 to battery and ground. As a result of the energization of the relay 333, an energizing circuit is completed for the normal signalling lamp 138 from ground through 55 battery at the office, Fig. 1, through the filament of the lamp 138, conductor 158 and the front contact and armature 337 to ground. The illumination of the lamp 138 indicates that the system is in its normal non-operating condition with the apparatus in prepa-

ration for an operation. A further result of the energization of the relay 333 is to prepare a starting circuit over the front contact and armature 338, as will be described in more detail hereinafter.

At the substation, as a result of the energization of relay 421 an energizing circuit is completed for the relay 419 from the negative side of the battery 429, Fig. 4, to the winding of the relay 419, the front contact and armature 430, to the positive side of the battery 429, over conductor 431. The energization of the relay 419, prepares an energizing circuit for the relay 420 which functions in a manner to be described in more detail hereinafter to 70 restore the apparatus to normal should the selecting relays at the office and substation fall out of step. A further result of the energization of the relay 421 is to prepare a locking circuit over the armature 432 in a 75 manner to be described in detail hereinafter.

It will be assumed for purposes of illustration that the dispatcher desires to operate the circuit breaker 617 from its tripped to its closed position. In order to perform this 80 operation, it is first necessary for the dispatcher to start the apparatus into operation by closing the start key, operating the stop key individual to the unit which he desires to operate in order to bring the selecting apparatus to a stop at the position individual to the circuit breaker 617, operate the individual operate key and finally when the unit has been reached operate the master control key to perform the desired operation. It 85 will be assumed therefore that the dispatcher momentarily closes the start key 137 and its contacts engage.

A circuit is thereupon completed from ground to battery, armature 340, Fig. 3, and 90 its back contact, through the winding of the relay 322, the back contact and armature 341, conductor 342, the contacts of the start key 137, conductor 159, and the back contact and armature 339 to ground. A multiple circuit 95 is completed for the lamp 136 over the contacts of key 137. This lamp illuminates to indicate that the system is in operation.

As a result of the energization of relay 322 over the circuit just traced, the original holding circuit for the relays 333 at the office and 105 421 at the substation is opened at armature 362' which has now moved from engagement with its back contact to engagement with its front contact. A further result of the energization of relay 322 is to prepare an operate circuit for the control line over armature 362' and its front contact and for the supervisory line over the armature 344 and its front contact. These circuits, however, are not completed at this 110 time for reasons that will be explained in detail hereinafter.

As a result of the deenergization of the relay 333 at the office, the energizing circuit 115

for the normal lamp 138 is opened at the armature 337 which has moved from engagement with its front contact to engagement with its back contact. At the same time an energizing circuit by-passing the start key 137 is completed for the green lamp 136 which indicates that the set is in operation from ground through battery through the filament of the green lamp 136 over the conductor 10 342 and the back contact and armature 337 to ground. A further result of the deenergization of relay 333 is to complete a circuit for the relay 322 by-passing the start key 15 from ground through battery, the armature 340 and its back contact through the winding 20 of the relay 322, the back contact and armature 341 and the back contact and armature 337 to ground. These circuits for relay 322 and lamp 136 are thus maintained 25 complete, even after the start key has been released to its normal open position.

A further result of the deenergization of relay 333 is to complete an obvious energizing circuit for relay 326. Relay 326 locks 25 over the contacts of key 102 and also completes a vibrating circuit for relays 324 and 325 which sequentially open each other's circuit and cause the lamp 101 to flicker. The dispatcher is then apprised that the system 30 has started into operation.

At the substation upon deenergization of the normal holding relay 421 normally energized over the holding circuit, an energizing circuit is completed for the relay 35 409 from ground over the armature 432 and its back contact through the winding of the relay 409, the back contact and armature 433, and battery to ground. As a result of the energization of relay 409, a circuit is prepared 40 for the control line over armature 428 and its front contact, but this circuit is not completed at this time for reasons that will be described hereinafter.

A further result of the energization of relay 45 409 is to complete a drive circuit at armature 431 for energization of the drive relay 414 at the substation and relay 314 at the office. This circuit is completed from ground at the office through battery over the back 50 contact and armature 345, the winding of the drive relay 314, the back contact and armature 346, the conductor 347, armature 348 and its back contact, the front contact and armature 349, armature 350 and its back contact, the drive line 351, the back contact and armature 434, at the substation, Fig. 4, armature 55 435 and its back contact, armature 431 and its front contact, through the winding of the relay 414 and armature 444 and its back contact to ground.

As a result of the energization of the relay 60 314 at the office, an energizing circuit is completed for the relay 316 from ground through battery, the winding of the relay 316, the armature 347 and its back contact, and the

front contact and armature 348 to ground. The energization of the relay 316 completes a locking circuit for itself from ground through battery, the winding of the relay 316, 70 front contact and armature 343, back contact and armature 351, conductor 355, back contact and armature 222, conductor 342, to the back contact and armature 337 to ground. A further result of the energization of the relay 316 is to complete an energizing 75 circuit from ground over the armature 353 and its front contact, through the winding of the relay 318, conductor 354 to negative battery and ground.

The energization of the relay 318 completes 80 an energizing circuit for the relay 313 from ground over the armature 353 and its front contact, the front contact and armature 355, the back contact and armature 356 through 85 the winding of the relay 313, the back contact and armature 357 and over conductor 354 to battery and ground. As a result of the energization of the relay 313, the original energizing circuit for the drive relay 314 90 is opened at armature 346.

During this period while the drive line is closed and the operations just described were being performed at the office, the drive relay 414 is energized at the substation in the manner described above. As a result of the energization of the relay 414, an energizing circuit by-passing the circuit traced above over the front contact of the normal holding relay 421, is completed for the relay 419 from 95 ground over the armature 436 and its front contact, through the winding of the relay 419 to the negative side of the battery 429. A further result of the energization of the relay 414 is to complete an energizing circuit 100 for the relay 416 from ground over the armature 437 and its front contact, armature 438 and its back contact, back contact and armature 441 and through the winding of the relay 416 to battery and ground. As a 105 result of the energization of relay 416, a locking circuit is completed for itself from ground through battery, the winding of relay 416, front contact and armature 443, the back contact and armature 442, conductor 439, the back contact and armature 520, conductor 521, and the back contact and armature 432 to ground.

When the drive line is now opened at the office as a result of the energization of relay 110 313 described above, the drive relays 314 at the office and 414 at the substation are deenergized. As a result of the deenergization of relay 314 at the office, an energizing circuit is completed for the relay 327 from 115 ground through battery, the winding of the relay 327, the front contact and armature 359, and to the back contact and armature 348 to ground. The relay 327 is energized over the circuit traced above, and completes 120 a locking circuit for itself from ground 125 to ground.

through battery, the winding of relay 327, front contact and armature 351, conductor 355, the back contact and armature 222, conductor 342, and the back contact and armature 337 to ground. A further result of the energization of relay 327 is to open the locking circuit for the relay 316 at armature 351. Relay 316 is deenergized which, in turn, opens the energizing circuit for the relay 318.

Upon deenergization of relay 318, the energizing circuit for relay 313 which was completed over armature 355 is opened. As a result of the deenergization of the relay 313, the original energizing circuit for the drive relay 314 over the armature 346 is again completed.

During this period while the drive line is open, upon deenergization of the relay 414, at the substation, an energizing circuit is completed for the relay 417 from ground, through battery, through the winding of the relay 417, the front contact and armature 440 and the back contact and armature 437 to ground. As a result of the energization of the relay 417, a locking circuit is completed therefor from ground through battery, winding of the relay 417, front contact and armature 442, conductor 439, back contact and armature 520, conductor 521, and the back contact and armature 432 to ground. A further result of the energization of the relay 417 is to open the locking circuit for the relay 416 at armature 442. The relay 416 is, as a result, deenergized.

A further result of the energization of the relay 417 is to complete an energizing circuit for the relay 425 from ground to battery, winding of the relay 425, the front contact and armature 440, and over the back contact and armature 432 to ground. The energization of the relay 425 completes a locking circuit for itself from ground through battery, winding of the relay 425, front contact and armature 454 to ground over the back contact and armature 432.

It will be noted that the first drive impulse did not energize a selecting relay as each succeeding drive impulse does. The purpose of this is to increase the reliability of the system, especially when a large number of selecting points are employed.

The relays 316, 317 and 327 at the office and the relays 416, 417 and 425 at the substation constitute dummy points. If there should be a momentary failure of battery when switching from one group to the next, the first ten selecting relays may be reoperated while the second group are being operated at the other station. Since under certain circumstances it may be desirable to employ the same check circuit repeated in the second group, such a condition would ordinarily not be detected. By providing a dummy point such as described above, the check circuit will fail on the first point and the apparatus restored, if

a condition such as described above occurred.

Upon the deenergization of the relay 313, a second drive impulse for the relay 314 at the office and the relay 414 at the substation, is transmitted over the circuit which has already been traced. As a result of the second energization of the relay 314 at the office, an energizing circuit is completed for the first selecting relay 210 from ground through battery, winding of the relay 210, conductor 257, armature 360 and its front contact and the front contact and armature 348 to ground. The energization of the first selecting relay completes a locking circuit for itself from ground, through battery, the winding of the relay 210, the first contact of the selecting relay 210, back contact and armature 221, the back contact and armature 225, conductor 342 and the back contact and armature 337 to ground.

At the substation, upon the energization of the relay 414 for the second time, an energizing circuit is completed for the first selecting relay 510 from ground through battery, to the winding of the relay 510, a conductor 525, armature 456 and its front contact, the back contact and armature 438 and the front contact and armature 437, to ground. As a result of the energization of the relay 510, a locking circuit is completed therefor, from ground through battery, to the winding of the relay 510, the first contact of the relay, the back contact and armature 526, back contact and armature 527, conductor 521, and the back contact and armature 432 to ground.

Upon the energization of the first selecting relay 210 at the office and 510 at the substation, a check circuit is completed depending on the energization of equivalent selecting relays at the office and at the substation. In the present instance, this circuit is completed from ground through battery, third contact of the selecting relay 210, the back contact and armature 358, through the winding of the check relay 319 at the office, the fourth contact of the selecting relay 210, conductor 261, back contact and armature 361, the front contact and armature 344, armature 373 and its back contact over the supervisory line 362, back contact and armature 445, armature 446 and its back contact, armature 447 and its front contact, armature 448 and its back contact, the conductor 449, to the fourth contact of the selecting relay 510, conductor 450 to the winding of the check relay 412, the armature 451 and its back contact, conductor 452 and to the third contact of the relay 510 to ground. The check circuit just traced, it will be noted, is completed from the negative side of battery, at the office, over the supervisory line, to the positive side of battery, at the substation. As will be pointed out in the description to follow, each pair of equivalent selecting relays in a group are provided with individual check circuits so that as each se-

lecting relay at the office and substation is energized, a check circuit is completed for indicating whether the correct selection has been made. As will be shown, only if the 5 correct selection has been made, will the proper operating circuits be completed for enabling performance of the desired operations. Had any other selecting relay than the first selecting relay at the office and station been 10 energized, the check circuit would not have been completed; thus, for example, if the first selecting relay at the office and the second selecting relay at the substation, had been energized simultaneously, the check circuit 15 would have been completed from ground to ground including no battery. Under other circumstances, no circuit is completed as, for example, where the selecting relay at the office prepares a check circuit through the control 20 line and the selecting relay at the substation prepares a check circuit through the supervisory line. Thus the circuit can be completed only when the equivalent selecting relays in the group are energized together at the 25 office and substation.

In the present case, it was assumed that the correct associated selecting relays were energized and as a result the proper check circuit was completed for energizing the 30 check relay 319 at the office and 412 at the substation. As a result of the energization of the check relay 319, an energizing circuit is completed for the relay 320 from ground over the armature 366 and its front contact, 35 through the winding of the relay 320 and battery to ground. As a result of the energization of the relay 320, a locking circuit is completed for this relay from ground to battery, through the winding of the relay 320, the 40 front contact and armature 375, and through the front contact and armature 348 to ground. A further result of the energization of the relay 320 is to complete an energizing circuit for the relay 321 from ground through battery, the winding of the relay 321, the front contact and armature 378, and the front contact and armature 348 to ground. The energization of the relay 321 functions to open the check circuit just traced for the relay 319 45 at armature 361 and to switch the control and supervisory circuits through to the final operating point, thereby preparing the selected circuit for operation.

At the substation the energization of the 50 relay 412 completes an energizing circuit for the relay 411, from ground through battery, the armature 467 and its back contact, winding of the relay 411, the front contact and armature 468, conductor 470 to the fifth contact of the first selecting relay 510 to ground.

As a result of the energization of the relay 55 411, a locking circuit is prepared therefor from ground through battery, the armature 467 and its back contact, through the winding 60 of the relay 411, front contact and armature

471 and through the front contact and armature 436 to ground.

A further result of the energization of relay 411 is to complete an energizing circuit for the relay 410 from ground to battery, 70 through the winding of the relay 410, to the front contact and armature 455, and the front contact and armature 436 to ground. The energization of relay 410 opens the energizing circuit for the check relay 412 at armature 75 448, thereby deenergizing the relay 412. A further result of the energization of the relay 410 is to complete the control and supervisory operating circuits.

Before describing, however, the operations 80 which take place on individual operate points, the operations which are performed whereby the succeeding selecting points are reached, will now be described. It will be noted that during the operations thus far traced, the 85 drive relay 314 at the office and 414 at the substation remained energized. An energizing circuit for the relay 313, it will be recalled, was completed over the armature 355 of the relay 318, which, in turn, is energized 90 over a circuit including the armature 353 of the relay 316. The relay 316, however, cannot be energized this time by reason of the fact that the relay 317 is energized, opening the energizing circuit for the relay 316 95 at armature 347.

A multiple circuit, however, is prepared at this time for the relay 318 over the armature contacts of the relay 321, and the contacts of the stop key. Assuming for the purposes of 100 illustration that the stop key individual to the first selecting relay was not operated to its open position but remains in the position shown, an energizing circuit is now completed for the relay 318 from ground through battery, shown in Fig. 2, over the conductor 354, the winding of the relay 318, armature 379 and its front contact, conductor 390, stop key, conductor 160, and through the fifth contact 105 of the first selecting relay to ground.

This circuit, it will be noted, is completed only if the stop key is in its closed or normal position and is completed immediately following the closing of the selecting relay contacts and energization of the relay 321 following the check operation which has been described in detail above. As a result of the energization of relay 318, a locking circuit is completed for this relay from ground 110 through battery over the conductor 354 and the winding of the relay 318, front contact and armature 391, over the conductor 390 through the stop key and over the circuit traced above through the contacts of selecting relay 210 to ground.

A further result of the energization of relay 318 is to extend the ground from the contact of the selecting relay over the armature 115 355 through the armature 356 and its back contact, the winding of the relay 318 and the 120 125

5 back contact and armature 357, to battery over the conductor 354 as stated above. Relay 313 is energized over this circuit and opens the drive circuit for relay 314 at the office and 414 at the substation at armature 346.

10 As a result of the deenergization of the drive relay 314, an energizing circuit is completed for the first switchover relay 200 from ground through battery, the winding of the switchover relay 200 over the conductor 268, the second contact of the selector relay 210 through conductor 269 and the back contact and armature 348 to ground. The switch-
15 over relay 200 is energized over the circuit traced above and completes a locking circuit for itself from ground to battery through the winding of the relay 200, front contact and armature 221, and the back contact and armature 225, conductor 342, through the back contact and armature 337 to ground. The energization of the relay 200 also switches the energizing circuit repeated by the drive relay 314 from its associated selecting relay to
20 25 the succeeding selecting relay 211, so that upon the next energization of the drive relay, the relay 211 instead of the relay 210 will be energized. A further result of the energization of the switchover relay 200 is to open the locking circuit for the selecting relay 210 at armature 221 and the locking circuit of relay 327 at armature 222.

30 At the substation, the deenergization of the relay 414 completes a locking circuit for the switchover relay 500 from ground over armature 437 and its back contact, conductor 469, through the second contact of the selecting relay 510, energized, and through the winding of the relay 500 to battery and ground. 35 As a result of the energization of the relay 500 a locking circuit is completed for itself from ground through battery, through the winding of the relay 500, front contact and armature 526, the back contact and armature 527, conductor 521, to ground over the back contact and armature 432. A further result of the energization of relay 500 is to open the locking circuit for the selecting relay 510, which, it will be recalled, was completed over 40 45 50 the back contact of armature 526, which has now moved from its back contact to its front contact. A further result of energization of relay 500 is to transfer the energizing circuit previously traced for the selecting relay 510 from the drive relay 414, through the switch-
55 over relay 500, to the succeeding selecting relay 511 so that upon the succeeding energization of the drive relay the selecting relay 511, instead of the relay 510 will be energized. The locking circuit for the relay 417 at armature 520 is opened at this time and this relay is deenergized.

60 Upon deenergization of the selecting relay 210 at the office, the energizing circuit for the relay 318 formerly traced through a contact

of the selecting relay 210 is deenergized. The deenergization of the relay 318 opens the energizing circuit for the relay 313, which, upon deenergization again closes the drive circuit for the relay 314 at the office, and 414 at the substation, at armature 346 and its back contact.

65 70 75 80 85 90 95 Drive relays 314 and 414, are now reenergized over the circuit previously traced, and circuits are again completed at the office and substation from ground, at the office, for example, over the armature 348 and its front contact to a selecting relay. This circuit, however, as will be noted from the circuit about to be traced, is completed through the succeeding selecting relays, from ground over armature 348 and its front contact, the front contact and armature 220, and through the winding of the selecting relay 211 to battery and ground. At the substation, the energization of the drive relay 414 completes an energizing circuit for the second selecting relay over a circuit from ground over armature 437 and its front contact, armature 438 and its back contact, the front contact and armature 535 and through the winding of the second selecting relay 511 to battery and ground.

95 100 105 110 115 120 125 As a result of the energization of the selecting relay 211 at the office, a locking circuit is completed for itself from ground through battery, through the winding of the selecting relay 211 through its first contact, the back contact and armature 224 and the back contact and armature 228, conductor 342, and the back contact and armature 337 to ground. At the substation, as a result of the energization of the selecting relay 511, a locking circuit is completed for itself, from ground through battery, the winding of the selecting relay 511, its first contact, the back contact and armature 536, back contact and armature 537 to conductor 521, and back contact and armature 432 to ground.

130 A check circuit will now be completed through the contacts of these associated selecting relays at the office and substation. Assuming, as has been described, that the selecting relay 211 has energized at the office, and the selecting relay 511 has energized at the substation, the check circuit now will extend completed from ground at the office through the third contact of the second selecting relay 211, the back contact and armature 358, through the winding of the check relay 319, over the fourth contact of the check relay 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 the substation, armature 451 and its back contact, conductor 452 through the third contact of the selecting relay 511 at the substation and through battery to ground.

5 It will be recalled that the check circuit traced for the first associated pair of selecting relays at the office and substation, was completed from battery at the office to ground at the substation over the supervisory line.

10 This check circuit, it will be noted, in turn, while being completed over the same supervisory line as the first check circuit was, is completed from ground at the office, to battery at the substation. In a similar manner, 15 each of the remaining pair of associated selecting relays is checked by an impulse individual to that particular pair of selecting relays in the group.

Upon energization of the check relay 319 20 at the office, the relay 320 is energized over the circuit traced above which in turn energizes the relay 321. The energization of the relay 321 transfers the control and supervisory lines through to their operating point 25 and at the same time deenergizes the check relay 319, this having all been described in detail above.

As a result of the energization of the check relay 412, at the office, an energizing circuit 30 is completed for the relay 411 which, in turn, completes an energizing circuit for the relay 410 in a manner which has already been described in detail above. The energization of the relay 410 transfers the control and supervisory lines through to the operating point 35 and at the same time energizes the relay 413 which, in turn, deenergizes the check relay 412 as was described in detail above.

The drive line is now opened in the manner described above, the relay 318 being energized over the contact of the succeeding selecting relay stop key. When the switch-over relay 201 is energized, it not only opens the energizing circuit of relay 211 and transfers the circuit from the drive relay to the succeeding selecting relay 212, but it also opens the energizing circuit for relay 200 which thereupon deenergizes. The same operations take place at the substation. Thus 50 it will be noted that not only are the selecting relays successively deenergized but the switch-over relays are also deenergized and only one selecting and switch-over relay is energized simultaneously for any length of 55 time.

It will be noted that the first two drive impulses thus far traced have both been completed from battery at the office to ground at the substation. In a similar manner, the 60 first four drive impulses are completed from battery at the office to ground at the substation. When, however, the fourth selecting relay has been energized and deenergized and the switch-over relay 203 is energized, a circuit 65 is completed for the relay 315 from ground

through battery, the winding of the relay 315, conductor 380, the front contact and armature 231, conductor 342, to ground over the armature 337 and its back contact. As a result of the energization of the relay 315, the 70 drive circuit is transferred from the negative side of battery to the positive side over the armature 345 and its front contact as distinguished from its original circuit to the negative side of battery over armature 345 and 75 its back contact.

At the sub-station, upon the completion of the fourth selecting operation the relay 415 is energized over a circuit from ground 80 through battery, through the winding of the relay 415, the front contact and armature 550, conductor 521, to ground over the armature 432 and its back contact. The drive circuit is thus transferred from the ground connection over armature 444 and its back contact to the negative side of battery over armature 444 and its front contact.

It will be noted from the drawings that the relay 315 is energized in multiple over the front contact and armatures of the relays 203, 85 204, 205 and 206, while at the substation the relay 415 is energized in multiple over the front contacts of relays 503, 504, 505 and 506. Thus, during the next four drive impulses and until the end of the eighth drive impulse 90 the current over the drive line is reversed in polarity from that described in detail above. During this period the four checking impulses transferred during the first group of 95 drive impulses are repeated. Since the polarity of the drive impulse is different, however, the combination of impulses for this group of selecting relays is different, from 100 that for the first group.

It will be noted also that the drive impulses thus far described have been transmitted over the conductor 351 and over the back contact and armature of 105 350, while the checking impulses have been transmitted over the conductor 362 over the back contact and armature 373. Following the energization of the eighth selecting relay and the eighth switch-over relay just before the ninth selecting operation, an energizing circuit is completed for the relay 323 from ground through 110 battery, the winding of the relay 323, through the front contact and armature 243 over conductor 342 to ground, through front contact and armature 337. As a result of the energization of the relay 323, the drive line is 115 now completed over armature 350 and its front contact, to conductor 362 instead of conductor 351, while the former drive line employing conductor 351 now functions as a checking line completed over armature 373 120 and its front contact.

Simultaneously, at the substation, following energization of the eighth selecting relay and the eighth switch-over relay, an energizing circuit is completed for the relay 408 125 130

from ground to battery through the winding of the relay 408 and through the front contact and armature 540 to ground over conductor 521 by way of back contact and armature 432. The energization of relay 408 switches the conductors 362 and 351 in a manner already described in connection with the operation at the office. Conductor 362 which formerly functioned as a supervisory conductor now operates as a drive line completed over the front contact and armature 434, while the conductor 351 formerly functioning as a drive wire now transmits supervisory signals over the front contact and armature 445. It will be noted that the relay 323 is energized in multiple over the front contact of the eighth and ninth switchover relays 207 and 208, while at the substation the relay 408 is energized in multiple over the front contact of the switchover relays 507 and 508. In this manner the ninth and tenth operating impulses are transmitted as drive impulses over the conductor 362 and supervisory impulses are transmitted at this time over the conductor 351.

In Figure 7, the manner in which the succeeding group of selecting relays at the office is started into operation by the apparatus in Figure 3 is shown in a diagrammatic manner. As will be clear from the above description, when the switch-over relay 209 is energized, a circuit is prepared for the first selecting relay 710 of the second group, and later completed over the front contact of armature 348. When the next succeeding impulse is received and relay 314 is energized, selecting relay 710 is energized. The first selecting relay at the substation is energized simultaneously with the relay 710. From this point on, the operation of the second group is identical with that of the first group, the only distinctions being in the absence of a dummy selecting position in the second group. The code which operates selecting relay 710, is the same as that which operates relay 210. The second selecting relay will be operated by the same code as that which operated relay 211, and etc.

It is evident, of course, that the switching over thus described can be repeated in the manner described for reversing the functions of the supervisory and control lines, and that this can be carried further by performing a further switchover operation for reversing the functions of the drive and control wires, etc. In this manner, a large number of variations can be obtained without repeating the same combinations of impulses at any one selecting position.

It has been assumed for the present illustration, that the dispatcher desires to close the breaker associated with the first selecting unit. In order to perform a close operation, the dispatcher will open the stop key individual to the first selecting position.

Upon operation of the stop key associated with the first selecting position, the energizing circuit for the relay 315 formerly traced over the stop key is not completed when the first selecting position is reached and the drive circuit remains closed. The first selecting relay at each station will be energized and the system will come to rest at this position.

If now the dispatcher operates the individual operating key 119 to the position for closing the circuit breaker, an energizing circuit is completed for the closing relay 303 from ground through battery, through the winding of the relay 303, conductor 281, through the right hand contact of the individual closing key 112, the right hand contact of stop key 105, the conductor 165, the sixth contact of the selecting relay 210, conductor 271, through the contacts of the master key 139, conductor 272, armature 381, and its front contact, the back contact and armature 382 and the front contact and armature 348 to ground. This circuit, it will be noted, is completed over the front contacts and armatures of relays which are energized only if the correct check circuit was completed, thus adding additional guard to the accuracy of the selecting operation.

As a result of the energization of the relay 303 which is energized in response to the operation of the individual key to its closed position, as distinguished from the energization of the trip relay 305 when the individual operating key is operated to its trip position, an energizing circuit is completed for the slow release relay 302 from ground through battery through the winding of the relay 302 over the back contact and armature 383, the front contact and armature 384, the armature 381 and its front contact, the back contact and armature 382 and the front contact and armature 348 to ground.

As a result of the energization of the relay 302, the first impulse for the operating control code is completed for energizing the relay 306 at the office. This circuit is completed from ground through battery, the back contact and armature 385, through the winding of the relay 306, the front contact and armature 386, the front contact and armature 361, front contact and armature 344, armature 373 and its back contact, conductor 362, back contact and armature 445, armature 446 and its back contact, armature 447 and its front contact, armature 448 and its front contact, armature 482 and its back contact, conductor 556 through the sixth contact of the selecting relay 510, conductor 557', and armature 631 and its front contact to ground.

At the substation, an energizing circuit is completed for the relay 400 from ground through battery over the back contact and armature 484 through the winding of the relay 400, the conductor 460, through the last

contact of the selecting relay 510, conductor 565, the front contact and armature 486, the front contact and armature 428, the control line 335, armature 362' and its front contact, 5 armature 391 and its front contact through the last contact of the selecting relay 210, the contacts 140 of the master control key, armature 385 and its back contact, back contact and armature 388, conductor 286, the closed 10 right hand contact of the stop key 104, conductor 160, and through the fifth contact of the selecting relay 210 to ground.

As a result of the energization of the relay 400 at the office, an energizing circuit is completed for the slow release relay 407 from ground to battery, winding of the relay 407, the front contact and armature 487, front contact and armature 480, front contact and armature 438, and the front contact and armature 437 to ground. 15 The energization of relay 407 completes an energizing circuit for the relay 402 from ground through battery through the winding of relay 402, the back contact and armature 488, front contact and armature 489, front contact and armature 490, the front contact and armature 480, front contact and armature 438, and front contact and armature 437 to ground. 20 As a result of the energization of relay 402, a locking circuit is completed therefor, from ground to battery through the winding of the relay 402, the front contact and armature 491, the back contact and armature 492, the front contact and armature 490 to ground 25 over the circuit traced above. A further result of the energization of relay 402, is to prepare an energizing circuit for the relay 401 at armature 492 and its front contact, but this circuit is not completed at this time for the 30 reason that the armature 489 is in engagement with its front contact.

At the office, the energization of the relay 306 completes an energizing circuit for the relay 307, from ground through battery, 45 winding of the relay 307, the back contact and armature 392, front contact and armature 393, front contact and armature 384, armature 381 and its front contact, back contact and armature 382, and the front contact and armature 348 to ground. As a result of the energization of the relay 307, a locking circuit is completed for this relay from ground to battery, the front contact and armature 394, the front contact and armature 384, and armatures 381 and 382 to ground over the armature 348 over the circuit traced above.

A further result of the energization of the 50 relay 307 is to open the circuit for the relay 400 originally traced over the armature 388. The relay 400, is, as a result, deenergized. Upon the deenergization of the relay 400, an energizing circuit is completed for the relay 55 401 from ground through battery, through the

winding of the relay 401, over the back contact and armature 493, front contact and armature 492, and over the back contact and armature 489 to ground over the front contact and armature 480 over the circuit traced 70 above. Following energization of the relay 407, an energizing circuit is completed for relay 406 from ground through battery, winding of relay 406, front contact of the first armature of relay 407, back contact and armature 487, front contact and armature 480, front contact and armature 438, and front contact and armature 437 to ground. The energization of the relay 401 completes 75 a locking circuit for itself from ground through battery through the winding of the relay 401, and the front contact and armature 473 to ground over the front contact and armature 490 traced above. A further result of the energization of relay 401 is to open 80 an additional point in the circuit of the relay 400 at armature 484 which now engages its front contact and to prepare a circuit for the relay 403 at the front contact and armature 488, which however, is not completed this 85 time by reason of the fact that the armature 489 is in engagement with its back contact.

The energization of the relay 401, at the substation, also opens the energizing circuit for the relay 306 at armature 484, which is 90 now in engagement with its front contact. The first two operation control code impulses are thus completed. Upon the deenergization of the relay 306, an energizing circuit is completed for the relay 309 from ground through 95 battery, through the winding of the relay 309, back contact and armature 398, back contact and armature 397, to ground over the front contact and armature 394 as traced above. 100

It will be noted from the circuits traced thus far, that the first operation for transmitting a code to close the circuit breaker, comprises transmitting an impulse from a battery of negative polarity at the office over 110 the control wire for energizing a relay at the station and from negative pole of the battery at the substation over the supervisory wire for energizing a relay at the office. These two relays upon energizing, complete 115 energizing circuits for their respective local relays which, in turn, upon energizing, each open the energizing circuit for one of the pair of relays mentioned above at the other station. That is, the local relay energized 120 at the office, opens the circuit for the relay at the substation which was energized over the line connecting the stations, whereas the local relay energized at the substation, opens the energizing circuit of the relay energized 125 at the office over a line connecting the stations. The first two relays are now again energized, but this time with energy of reverse polarity. By this arrangement, unless the correct impulse has been completely received 130

at the remote station so as to energize the correct relay thereat, the operations will stop. An ingenious arrangement is thus provided for maintaining two remotely disposed chains of relays in synchronism. In the particular arrangement disclosed, this is applied for operation control although it will be understood that the synchronous operation can be applied for any desired purpose such as supervisory control selection of units point by point. The next impulse transmitted between the stations is now completed from the ground at the office over armature 348, its front contact and armature 381, armature 396 and its back contact, the front contact and armature 385 through the winding of the relay 306 and over the circuit traced above including the supervisory line to the substation, and over the circuit traced above at the substation, including armature 448 and its front contact, the armature 482 and its front contact, the back contact and armature 494, the back contact and armature 495, the front contact and armature 496, the front contact and armature 475, the front contact and armature 498, to battery and ground.

Similarly, the relay 400 has now a circuit completed from ground over the armature 437 and its front contact, the armature 438 and its front contact, armature 480 and its front contact, the front contact and armature 484 through the winding of the relay 400 over the circuit traced above over the control line to armature 391 and its front contact, over the circuit traced above, to the armature 387 and its front contact, instead of the back contact as traced above and over the back contact and armature 399 to battery and ground. As a result of the energization of the relay 306 at the office, and the relay 400 at the substation, a second time as a result of the transmission of the third and fourth code impulses, the relay 310 at the office is energized over the front contact of armature 392 and the front contact and armature 393, over the same circuit as traced above for the relay 307. The energization of the relay 310 opens the circuit for the relay 400 at armature 399, causing this relay to deenergize.

50 The energization of the relay 400 at the remote station a second time completes an energizing circuit for the relay 403, over the back contact and armature 497, the front contact and armature 488 and front contact and armature 489 and thereafter over a similar circuit traced for the relay 401 above. The energization of the relay 403 completes a locking circuit for itself over armature 499 and prepares an energizing circuit for the relay 404. Upon the deenergization of the relay 400 as described above, an energizing circuit is completed for the relay 404 over the front contact of armatures 493, 492, and the back contact of armature 489 over the same circuit as traced above for the relay 401. The

energization of the relay 404 prepares an energizing circuit for the relay 405 and opens the circuit for the relay 393 at armature 495.

55 In this manner the code of impulses for performing the closing or tripping operations are transmitted from the first to the second stations. Although any combination of code impulses can be transmitted, for purposes of illustration only, as illustrating the preferred modification, three impulses are transmitted for performing a trip operation and five impulses are transmitted for performing a closing operation.

60 In the present illustration it is assumed that the dispatcher desires to close the tripped circuit breaker 617. As a result five code impulses are transmitted for performing the closing operation. Upon the transmission of the fifth code impulse for the operation control, the relay 311 at the office is energized and upon energization opens the energizing circuit for the relay 302 at armature 383. As a result of the deenergization of the relay 302, the energizing circuit for the relay 306 which is prepared at this time over the front contact of armature 386 is now opened and this relay remains deenergized. Relay 400 on the other hand continues energized during the operation of the fourth and fifth relays 310 and 311 at the office, the circuit therefor being completed over back contact and armature 399 through battery to ground as traced above when the relay 310 is deenergized and over the front contact and armature 376 to battery and ground when the relay 311 is energized. As a result of the relay 400 remaining energized for more than the usual signalling period, the relay 406, whose energizing circuit it will be recalled, was traced over the back contact of armature 487, becomes deenergized by reason of the length of period its circuit is open, while armature 487 is in engagement with its front contact.

65 After a period of time this relay deenergizes and an operating circuit for performing the closing operation is completed from ground through battery over the armature 498 and its front contact, the armature 475 and its front contact, armature 496 and its back contact, armature 590 and its front contact, and over the conductor 598 through the seventh contact of the selecting relay 510, conductor 598, and through the winding of the relay 612 to ground. As a result of the 70 energization of the relay 612, an obvious energizing circuit is completed for the solenoid 614 which in turn completes an obvious energizing circuit for the operating magnet 615 to operate the circuit breaker 617 from its tripped position to its closed position. If this circuit breaker had been closed and it had been desired to trip the circuit breaker it would merely have been necessary to move the operating key to its trip position. In 75

such a case, the relay 305 would have been energized instead of the relay 303. Relay 305 and relay 304, it will be noted, are energized in multiple. The relay 304 by operating its armature 396, limits the number of operating control code impulses transmitted to three. At the end of the code impulses, the relay 400 remains energized to deenergize the relay 406 in the manner described above. 5

Upon deenergization of the relay 406, the operating circuit is completed as described above except that the armature 590 in this case, is on its back contact, since relay 405 is not energized. Upon tracing the circuit 10 from the back contact of the armature 599, it will be noted that this circuit is completed through the trip coil 611. In this manner, either a close or trip code can be transmitted for operating the circuit breaker. 15

It will be noted further that the circuit 20 for the closing winding 303, was traced through the contacts of the master control key. It will be evident therefore that the master control key must be maintained closed 25 until the indication comes back of the operation or else no operation will be performed. In other words, should a smaller number than the required number for a particular operation desired be transmitted, when the master 30 key is released, no operation will be performed and the apparatus will merely restore to its condition before the code was transmitted. In such a case the relay 400 will be deenergized, thereby opening the energizing 35 circuit for the relay 407 which, in turn deenergizes after an interval of time to deenergize the relay 406. Since the relay 407 deenergizes first, no operating circuit can be completed. If, on the other hand, the master 40 key is maintained closed until the unit has operated, upon the opening of the master key, the relay 305 is deenergized and opens the energizing circuit for the relay 400. The deenergization of the relay 400 opens the energizing circuit for the relay 407 which, after 45 an interval of time, deenergizes. The deenergization of the relay 407 opens the energized locking circuit for all of the code relays at the station which thereupon are deenergized. Similarly at the office, upon deenergization of the relay 303, in case of a closing 50 operation of the relay 302 and relays 304 and 305 in case of a tripping operation, all of the code relays which are locked over the 55 armature of these relays are deenergized and restored to normal.

Upon operation of the circuit breaker to its closed position, the circuit for relay 601 is opened which, upon deenergization, opens 60 the circuit for relay 600. Upon deenergization of relay 600, a supervisory circuit is completed from ground through battery, over the back contact of armature 631, conductor 557, sixth contact of selecting relay 510, conductor 556, back contact and armature 482, 65 over armatures 410, 447, 446 and 445 to supervisory line 362, over armatures 373, 344, 361, armature 386 and its back contact, back contact and armature 389, armature 380, and its back contact conductor 297, the seventh contact of selecting relay 210, conductor 171, armature 142 and its back contact, and through the winding of relay 300, back contact and armature 367, contacts of key 134 and over conductor 188 to ground. 70

Energization of relay 300 opens the circuit for relay 313 at armature 357, thus preventing operation of the drive circuit at this time and completes an energizing circuit for relay 141 from ground through winding of 80 relay 141, contact of relay 210, conductor 281, armature 368, and its back contact, front contact and armature 357, conductor 354 to battery and ground. This relay, upon energization, locks itself over armature 144, opens 85 the circuit for lamp 116 and closes a circuit for lamp 115 whereby the dispatcher is apprised of the operation. A further result of energization of relay 141 is to open the circuit for relay 300. This relay deenergizes 90 and an energizing circuit is completed for relay 313. The drive circuit is thereupon opened for operation to the succeeding step if the stop key has been released. 95

Had the above described supervisory signal been received as a result of an automatic operation, the stop key would ordinarily have been in a non-operated position. Nevertheless, the selecting operation would have been brought to a stop by energization of a relay 100 105 as will be described in more detail hereinafter in connection with the description of operation following an automatic operation.

While a transmission of a code in the manner described above is exceptionally desirable 110 in a synchronous relay system of the kind described above for increasing the accuracy of the system and making infallible its operation, the arrangement would have a drawback in the case where remote synchronization is 115 desired. In cases of remote synchronizing, it is essential when the two alternating current systems which are to be connected together when in synchronism have reached the necessary synchronism and phase relations, that the impulse for connecting the system be immediately transmitted before the systems again fall out of synchronism. This could not be accomplished by the transmission of a code combination of impulse as described above, because of the time involved. On the other hand, it is undesirable to leave this selecting point subject to inductive surges by wiring it for direct operation by a single impulse. In order to overcome this difficulty, an arrangement has been provided for presetting the operation control apparatus; that is, circuit arrangements are provided for transmitting the operation control impulses 120 125 on the preceding selecting position at which 130

the supervisory impulses operating the synchroscope are received, and as soon as the systems are in synchronism, it is only necessary to transmit a single impulse for connecting 5 the systems. Thus for example, if it were desired to connect two power systems 630 and 631 when in synchronism, it would be first necessary to determine when the two systems are in synchronism. In order to obtain the 10 readings for operating the synchroscope at the office, the stop key associated with the second position in the selecting system is operated to its open position and the stop key operated in a manner described above so that 15 the system operates until the second selecting relay at the office and at the substation are energized. The operation control code is then transmitted for performing a closed operation and five impulses are transmitted 20 over this system.

Upon the energization of relay 405 in the manner described above, a circuit is completed for the relay 602 from ground through battery, the winding of the relay 602, conductor 633, through the last contact of the 25 second selecting relay 511, conductor 588, the front contact and armature 477, conductor 555, conductor 635, the front contact and armature 520, conductor 521, and the back contact 30 and armature 432 to ground. As a result of the energization of the relay 602, a locking circuit is completed for this relay from ground through battery, the winding of the relay 602, front contact and armature 636, and over conductor 633 to ground at armature 432 as traced above. A further result of the energization of relay 602 is to 35 prepare an energizing circuit for the relay 603 from ground through battery, through the winding of the relay 603, armature 638 and its front contact, conductor 637, back contact and armature 477, conductor 555, and over conductor 635 to ground over the armature 432 as traced above. This circuit, it will 40 be noted, is not completed until the end of the transmission of the operation control code impulses at which time the relay 405 deenergizes in the manner described above. Upon 45 energization of the relay 603 over the circuit traced above, a circuit is completed for the winding 638' of the potential transformer, extending from the common return line, Fig. 4, conductor 468, armature 641 and its front contact, winding 638', the front contact and armature 642, the conductor 557, the sixth 50 contact of the selecting relay 511, conductor 556, back contact and armature 482, front contact and armature 448 front contact and armature 447, back contact and armature 446, the armature 445 and its back contact, supervisory conductor 362, back contact and armature 373, the armature 344 and its front contact, armature 361 and its front contact, armature 386 and its back contact, back contact and armature 389, the armature 380 and

its back contact, conductor 297, the seventh contact of the selecting relay 211, the armature 147 and its front contact to the synchroscope 145. A similar circuit is completed for the winding 639 coming from ground over 70 the armature 641 as traced above and its front contact, through the windings 638' and 639 in series over the front contact and armature 644, conductor 645 through the next to last contact on the selecting relay 511, conductor 565, the front contact and armature 486, front contact and armature 428, control line 335, the armature 362 and its front contact, the armature 394 and its front contact, a contact of the second selecting relay 211, conductor 198, the armature 148 and its front contact, to the contact of the synchroscope and over 80 the front contact and armature 146 and conductor 196 to the common return line. In this manner synchroscope readings can be obtained of the relative synchronous positions 85 of the two circuits which are connected together. When now, the two systems are in synchronism, it is desirable that the circuit breaker associated with the proper unit be 90 closed immediately.

A further result of the energization of the relay 602 is to complete an energizing circuit for the relay 604 from ground at armature 437, Fig. 4, and its front contact, armature 438 and its front contact, armature 480 and its front contact, over the conductor 596, armature 666 and its front contact, the armature 667 and its front contact, through the winding of the relay 604 conductor 568, to back contact and armature 433 and battery to ground. As a result of the energization of relay 604 over the circuit just traced, an energizing circuit is completed for the relay 664 from ground over the armature 665 and its front contact, through the winding of the relay 664 and over conductor 568 to the negative side of battery at armature 433 as traced above.

A further result of the energization of the relay 604 is to complete a locking circuit for itself from ground over the armature 665' and its front contact and through the winding of the relay 604 to the negative side of battery over conductor 568 as traced above.

A circuit is now prepared for the closing relay 608 which will be completed when the third selecting relay in the system is energized as will be described hereinafter. When the system is in synchronism and the dispatcher is ready to close the circuit breaker he will open the stop key for the third position and at the same time close the stop key for the second position. As a result, the operations as described above for performing a stepping operation in the selecting system will step the system to the third selecting relay at the office and substation which will energize simultaneously.

When the third selecting relay at the sub-

station energizes, a circuit is completed from ground through battery to the winding of the relay 608, conductor 682, through the last contact of the third selecting relay 512, conductor 5 686, the front contact and armature 686' and to ground over conductor 596 as traced above. As a result of the energization of the relay 608 an energizing circuit is completed for the solenoid 610 which in turn completes an obvious energizing circuit for the operate magnet 618 to close a circuit breaker. In this manner, although the operation control employing a code combination of impulses, operates to close circuit breakers and consumes 10 a comparatively long period of time, nevertheless for closing a circuit breaker when the two systems to be connected are in synchronism, it is necessary to transmit only a single impulse for performing the necessary closing operation thus considerably reducing the operating time.

Should a circuit breaker automatically operate, it is necessary in order to transmit the supervisory signal, to start the chain into operation. For purposes of illustrating how this is accomplished, it will be assumed that the circuit breaker 617 automatically operates to its trip position. Upon the tripping of the circuit breaker the energizing circuit 25 for the relay 601 is completed which in turn completes the energizing circuit for the slow operate relay 600. Since the slow operate release relay 600 energizes at a slower rate than the relay 601, a circuit is completed before the 30 relay 600 is completely energized from ground over the armature 660 and its front contact, the back contact and armature 661, over conductor 662, the armature 481 and its back contact, and through the winding of the relay 35 409 to the back contact and armature 433 and battery to ground. As a result of the energization of 409, the holding circuits for the relays 421 at the substation and relay 333 at the office, is opened and these relays deenergize.

40 Upon deenergization of these relays, the chains are started into operation in a manner described above until the selecting relay individual to the particular unit which is operated, in this case, circuit breaker 617, is 45 reached at which point a supervisory signal is transmitted to the office in a manner which has been described in detail above for changing the signalling lamp, thereby indicating to the dispatcher the change of operation which 50 has taken place at the substation. The above operation takes place when a change in the unit takes place while the system is at rest.

If a circuit breaker should operate while the system is in operation, provision must 55 be made for preventing loss of this supervisory signal without operating the receiver supervisory lamp. This is accomplished by means of the relays 426 and 427 at the substation. For purposes of illustration, it will 60 be assumed again that the circuit breaker 617

operates from its closed to its trip position during the period while the selecting apparatus is in operation. The relay 601 will energize and before the relay 600 energizes, a 70 circuit is completed over the circuit as described above. It will be recalled, however, that relay 425 was energized following the first operation of the selecting apparatus. The circuit from the breaker is therefore completed from ground over the armature 660 75 and its front contact, the back contact and armature 661, conductor 662, armature 481 and its front contact the armature 466 and its back contact and through the winding of the relay 426 to battery and ground. The 80 energization of the relay 426 completes a locking circuit for itself from ground through battery, to the winding of the relay 426, back contact and armature 466, the front contact and armature 483, and the positive side of the battery 429. A further result of the energization of the relay 426 is to 85 prepare an energizing circuit for the relay 427 at armature 464, which circuit, however, is not completed at this time, for the reason that the system being in operation, the relay 421 is deenergized and the armature 432 is in engagement with its back contact.

During the operation of the system, the relay 426 therefore remains energized. At 90 the end of the operating period the apparatus is restored to normal in the manner described above and the relay 421 is energized. Upon the energization of the relay 421, an energizing circuit is completed for the relay 427 from 95 ground through battery, the winding of the relay 427, the armature 464 and its front contact, and front contact and armature 432 to ground. A further result of the energization 100 of the relay 427 is to open the locking circuit for the relay 426 at armature 466 to complete a locking circuit for itself at armature 465 and to prepare a circuit for the relay 409 at armature 463. Upon the deenergization of 105 the relay 426, the energizing circuit for the relay 409 is completed from ground over armature 463 and its front contact, armature 461 and its back contact and through the winding of relay 409 to the back contact and armature 433 and battery to ground. The 110 energization of the relay 409 starts the chain of relay selecting apparatus into operation, again deenergizing the relay 421. Upon deenergization of the relay 421, the locking circuit for the relay 427 is opened and the relay 426 and 427 are thus again restored to normal condition. The selecting apparatus now 115 operates until the operated unit is reached and a supervisory signal is sent in the manner described in detail above for operating the signal lamp individual to the unit.

When a unit has automatically changed its condition and the selecting apparatus has started, it is important that the selecting apparatus should not step over any point at 120 125 130

which a supervisory signal is to be sent before the supervisory receiver has correctly operated in accordance with the signal. It will be recalled from the above detailed description that if a unit changed to a closed position, relay 300 was energized when the selecting apparatus reached the unit and if a trip operation had taken place, relay 312 was energized, which in turn energized relay 301.

- 10 It will be noted that relay 313, which opens the drive line for stepping the selecting apparatus to its next position, completed its circuit over the back contact and armature of relays 300, 312 and 318.
- 15 Upon the energization of the selecting relay, relay 318 energizes as described above. If a supervisory signal is being sent, either relay 312 or 300 energizes. The circuit for relay 313, although prepared at the armature 20 of relay 318, is therefore maintained open at the armature of either relay 312 or 300, depending on the character of the supervisory signal. When the individual supervisory signal has been received, however, the relay 25 300 or 312 is deenergized in the manner described above and the circuit for relay 313 is completed. This insures that the supervisory signal will not be lost.

- Following the energization of all of selecting relays, an energizing circuit is completed at the office for the relay 331 from ground through battery, the winding of the relay 331, conductor 232, the armature 247 and its front contact, conductor 282, back contact and armature 352 and the back contact and armature 337 to ground. Upon energization of the relay 331, a locking circuit is completed for this relay from ground through battery, the winding of the relay 331, front contact 40 and armature 341 and the back contact and armature 337 to ground. A further result of the energization of the relay 331 is to open the energizing circuit for the relay 322 at armature 341, which thereupon deenergizes.
- 45 At the substation, when the last selecting relay is energized, the drive line is opened at the end of the impulse period and the relay 414 deenergized. It will be recalled that during the period while the relay 414 is energized, an energizing circuit is completed for the relay 419 over the front contact of armature 436 of the relay 414. Since the relay 414 remains energized for comparatively longer intervals compared to its deenergized interval, while the selecting apparatus is operating and the drive line remains closed during the operating period, the slow release relay 419 will normally not deenergize during these intervals. It will also be recalled that upon the 50 first energization of the slow release relay 419 following the first energization of relay 414, an energizing circuit was completed for the relay 420 from ground through battery, to the winding of the relay 420, the front contact 55 and armature 457, to the positive side of bat-

tery 429. The relay 420, upon energization locked itself over an obvious circuit including the front contact of its armature.

At the end of the last selecting impulse when the relay 414 deenergizes, for a period 70 longer than the normal deenergizing period of the drive line, the relay 419 is deenergized and permits its armature 457 to drop to its back position. Upon the deenergization of the relay 419, an energizing circuit is completed for the relay 419 from the negative side of the battery 429, through the winding of the relay 418 and armature 482 and its front contact, and the back contact and armature 457 to the positive side of the battery 429. Upon 80 the energization of the relay 418, the energizing circuit for the relay 409 is opened and this relay deenergizes. Upon deenergization of the relay 409 and the deenergization of the relay 422 described above, the original holding circuit for relay 333 and 421 is again completed and these relays energize. Upon energization of these relays the holding and locking circuit for all relays at their respective stations are opened and the apparatus is 90 restored to normal.

Although the selecting apparatus is arranged to operate in synchronism, it may happen that for some reason due to some extraneous effect or a break down in the local circuit, 95 a wrong selecting relay may be energized and throw the apparatus out of synchronism, that is, a relay such as the second selecting relay at the office may be energized simultaneously with the energization of the first selecting relay at the substation. Under such circumstances with a non-synchronous condition of this character, it is desirable to prevent the operating circuits from being completed and to stop further operation of the selecting apparatus. This is accomplished by relays arranged to detect when the selecting relays are 105 in synchronism at the office, and at the substation, and stop all operations as soon as they fall out of step and to restore the selecting apparatus to their normal non-operating condition.

It will be recalled that check relay 412 at the substation is energized following each selecting operation. Upon energization of the relay 412 an energizing circuit was completed for the relays 411, 410 and 413. Upon energization of relay 410, the energizing circuit for the relays 411, 412 and 413 are opened. If, however, a non-synchronous condition occurs, the circuit of the relay 412 will not be completed. As a result the relays 410 and 411 and 413 will not be energized. An energizing circuit, under these circumstances, will be completed for the relay 423 from ground through battery, the winding of the relay 423, the armature 475 and its back contact, the back contact and armature 478, and over the conductor 470 to the contact of energized selecting relay and to ground. This circuit would be com- 130

pleted for each selection, except for the fact that as soon as the selecting relay is energized, an energizing circuit should be completed for the relay 412, which upon energization opens 5 the circuit traced above at armature 475.

The momentary circuit thus completed under ordinary circumstances is not sufficient to energize relay 423. When a non-synchronous condition occurs, the relay 412, however, does 10 not energize, and therefore an energizing circuit is maintained for the relay 423 until this relay energizes. It will be recalled at this time that upon the first energization of the relay 412, an energizing circuit was completed 15 for relay 419, which in turn completed an energizing circuit for relay 420.

The energization of relay 423 completes a locking circuit for itself from ground through battery, the winding of the relay 423 and the 20 front contact and armature 458 back contact and armature 430 to positive battery. A further result of the energization of relay 423 is to open the circuits for the relays 411 and 413 at armature 467 so as to prevent accidental 25 energization of these relays at this time. An energizing circuit is also completed for the relay 418 from the negative side of the battery through the winding of the relay 418, the armature 482 and its front contact, and the armature 453 and its front contact, front contact and armature 458, the back contact and armature 430, to the positive side of battery.

The energization of the relay 418 open the energizing circuit for the relay 409 which 30 thereupon deenergizes and prepares an energizing circuit for the normal holding relay 421.

At the office, upon failure of the relay 319 to energize, due to the fact that the apparatus 35 is out of synchronism, and the check circuit fails, as noted above, the signal lamp 135 which ordinarily flickers as the selecting apparatus operates and remains illuminated during the operating period, its circuit being 40 completed over armatures 378 and 314, is now extinguished since relay 320 does not energize. The dispatcher is thus advised that the apparatus is out of synchronism. He is, at the same time, able to determine the position 45 of the selecting apparatus at which it fell out of step and thus to easily trace the trouble. The dispatcher now operates his reset key 134 to energize the reset relay 334. Energization of the relay 334 opens the circuit for the relay 50 322 which upon deenergization completes the normal holding circuit for the relays 333 and 421, which was previously prepared by the deenergization of relay 410, as was described in detail above.

55 The energization of relays 333 and 421 opens all the locking circuits at their respective stations and the apparatus is restored to normal.

Although I have described my invention as 60 applied to a supervisory control system, it is

obvious that it has broader application, such as in other well-known signalling systems, and I do not intend to limit myself by the specific disclosure but only insofar as set forth in the appended claims. 70

I claim as my invention:

1. In a signalling system, a first station, a second station, a chain of relays at each of said stations, a plurality of signalling lines connecting said stations, means at one of said stations for impressing an impulse on one of said signalling lines, means at said other station for impressing an impulse on another of said signalling lines simultaneously with said first mentioned means, means responsive to 80 said impulses for operating the relays at each station and means at the station remote from the station at which each of said impulses are impressed for terminating said impulses upon proper receipt thereof whereby said relays 85 are maintained operated in synchronism.

2. In a supervisory control system, a first station, a second station, apparatus units at said second station, synchronous selectors at each of said stations for sequentially associating said apparatus units for operation from said first station, means operative following the selection of one of said apparatus units for operation, for transmitting a code combination of impulses, means for operating said selected apparatus unit in response to said code combination of impulses, means including said synchronous selectors for selecting another of said apparatus units for operation and means automatically responsive to said selection for operating said other apparatus unit only after the transmission of an impulse code for said first mentioned unit. 90

3. In a signalling system, a first station, a second station, a plurality of groups of relays at each of said stations, means for operating said relays at each of said stations in synchronism, means including a check circuit for transmitting a code of impulses individual 100 to each relay in a group for identifying the relay in said group which is energized, said check circuits being repeated in the succeeding group and means for preventing energization of corresponding relays in non-associated groups simultaneously at each station 105 to control the check circuits. 110

4. In a signalling system, a station, a plurality of groups of relays at said station, means for energizing said relays sequentially, a check circuit for identifying the energized relay, said check circuit being individual to each relay in a group and means for repeating said check circuit in the same sequence but in relatively different positions in the second group whereby the equivalent numbered relay in each group does not have the same check circuit. 120

5. In a signalling system, a plurality of relays, means for energizing said relays se- 125 130

quentially, a check circuit individual to each relay in a group, means for repeating said check circuit for the relays in the succeeding groups, and means for changing the relative 5 position of each check circuit in different groups whereby the equivalent numbered relays in each group do not have the same check circuit.

6. In a supervisory control system, a first 10 station, a second station, a plurality of apparatus units at said second station, synchronous selectors at each of said stations, means for operating said selectors in synchronism for sequentially conditioning said apparatus 15 units for operation, means following the selection of any one of said apparatus units for transmitting a code of impulses, means responsive to said code of impulses for operating said selected apparatus unit, means 20 for positioning said selecting apparatus on a position preceding the selecting position of one of said apparatus units, means for transmitting said code for operating said apparatus unit, means for operating said selector to the succeeding selecting position and 25 for simultaneously operating said selecting unit, said last mentioned means being non-operative to operate said unit, except when said code has been transmitted while said 30 selectors are on the preceding selecting position.

7. In a supervisory control system, a first station, a second station, a plurality of groups of chains of relays at each of said 35 stations, each group in any one station comprising a different number of relays from that of the other group thereat but of the same number as the equivalent of the group at the remote station, means for transmitting 40 code combinations of impulses between said stations, means responsive to said code for operating said relay chains at each station in synchronism, said code differing for each of the relays in any one group but the same 45 for equivalent relays in the other group, whereby only the equivalent groups can be operated simultaneously.

8. In a supervisory control system, a first 50 station, a second station, synchronous selectors at each station, apparatus units at said second station, power systems controlled by one of said units, a control line connecting said stations, a supervisory line connecting said stations, means including said selectors for selecting one of said apparatus units, means 55 responsive following the selection of said unit for transmitting code combinations of impulses over said control line, means responsive to the code combination of impulses 60 for operating said apparatus unit, means responsive to the operation of said apparatus unit for transmitting a supervisory signal over said supervisory line, a signalling device operating in response to said supervisory signal, means including said synchronous 65

selectors for selecting the apparatus unit which controls said power systems, means for transmitting code combination of impulsive conditions for conditioning said unit for operation, means for transmitting supervisory signals over said control and supervisory line at said selected position in accordance with the phase and synchronism of said power systems, a synchronism-indicating device at said first station responsive to said impulses transmitted over said control and supervisory line for indicating the phase and synchronism of said power systems, and means for simultaneously operating said synchronous selectors and said conditioned apparatus unit for connecting said power systems.

9. In a signal system a first station, a second station, a plurality of groups of relays at each of said stations, means for operating said relays at each of said stations in synchronism, means including a check circuit for transmitting a code combination of impulse conditions individual to each relay in a group for identifying the relay in said group which is energized, said check circuits being repeated in succeeding groups and means comprising a dummy selecting position for preventing energization of corresponding relays in non-associated groups simultaneously at each station to control the check circuits.

10. In a supervisory control system, a first station, a second station, synchronous selectors at each of said stations, means for operating said selectors in synchronism, apparatus units at said second station, a signalling line connecting said stations, said selectors when operating in synchronism sequentially associating each of said apparatus units with said signalling line, means operative following the association of any one of said apparatus units with said signalling line for transmitting code combinations of impulses to said second station, means responsive to said code for operating said selected apparatus unit, a second signalling line connecting said stations, a plurality of alternating current power systems, an apparatus unit associated with a predetermined selecting position for connecting said power systems, means operative following the operation of said synchronous selectors to said predetermined selecting position for transmitting code combinations of impulses, means responsive to said code combinations of impulses for preparing said apparatus unit for operation, means for transmitting signals over both of said signalling lines from said second station to said first station under control of currents in said alternating current systems, means responsive to said signals for indicating relative synchronism of the currents of said alternating current power systems and means for simultaneously operating the selectors to the succeeding selecting posi- 130

tion and for operating said apparatus unit to connect the power circuits.

11. In a supervisory control, a first station, a second station, synchronous selectors at each of said stations, apparatus units at said second station, signalling devices individual to said apparatus units at said first station, a drive line connecting said stations, means for transmitting impulses over said drive line, means responsive to said impulses for operating said selectors in synchronism, means including said selectors at each selecting position for transmitting supervisory signals in accordance with the condition of the apparatus unit associated with the selecting position in the event that the signal device individual to said unit does not agree with the condition of said unit, means responsive to the transmitting of said impulse for momentarily preventing further transmission of said drive line impulses and means responsive to the operation of said signalling device in accordance with the impulse transmitted by said apparatus unit for starting said drive line into operation again.

12. In a supervisory control system, a first station, a second station, synchronous selectors at each of said stations apparatus units at said second station, signalling devices individual thereto at said first station, a drive line connecting said stations, means for transmitting impulses over said drive line, means responsive to said impulses for operating said selectors in synchronism to successive selecting positions, means at each selecting position for transmitting impulses from said apparatus units to said signalling devices in accordance with the condition of said apparatus units in the event that said signalling devices do not agree with the condition of said apparatus units, relay means at said first station responsive to said impulses for maintaining said drive line momentarily non-operative, and second relay means controlled by said first relay means for operating said signalling device in accordance with the condition of its associated unit and for simultaneously rendering said drive line operative again.

50 In testimony whereof, I have hereunto subscribed my name this 28th day of July, 1927.

ALBERT L. MOREAU.
